[57] CLAIM

The ornamental design for a platter or similar article, as shown and described.

DESCRIPTION

FIG. 1 is a top plan view of a platter or similar article showing my new design;

FIG. 2 is a sectional view thereof taken along line 2—2 of FIG. 1 looking in the direction of the arrows;

FIG. 3 is a bottom plan view thereof on a reduced scale, wherein the floral decoration and rim decoration have been eliminated for ease of illustration; and

FIG. 4 is a sectional view taken along lines 4—4 of FIG. 1 looking in the direction of the arrows.

FIG. 1.

FIG. 2.

FIG. 3.

FIG. 4.
